Filed May 11, 1960, Ser. No. 60,547

Term of patent 14 years

(Cl. D48—20)

fig.1.

fig.2.

FIGURE 1 is a front view of a combined guard and lamp for grinding machine or the like embodying the new design with its shield in guard position;

FIG. 2 is similar to FIG. 1 but shows the shield lifted to expose the illuminating surface of the combined guard and lamp for grinding machines or the like;

FIG. 3 is a side view of the combined guard and lamp for grinding machines or the like as seen in FIG. 2;

FIG. 4 is a rear view of the combined guard and lamp for grinding machines or the like as seen in FIGS. 2 and 3; and

FIG. 5 is a top view of the combined guard and lamp for grinding machines or the like shown in FIG. 4 and is partially in section with the section being taken along line 5—5 in FIG. 4.

The side of the combined guard and lamp for grinding machines or the like not illustrated is substantially the same in appearance as the side shown.

I claim:

The ornamental design for a combined guard and lamp for grinding machines or the like, substantially as shown and described.
